UNITED STATES PATENT OFFICE

154,899

DESIGN FOR A TOILET PAPER DISPENSER

Clarence Boord, Leon, Iowa

Application July 10, 1947, Serial No. 140,176

Term of patent 14 years

(Cl. D4—3)

To all whom it may concern:

Be it known that I, Clarence Boord, a citizen of the United States, residing at Leon, in the county of Decatur and State of Iowa, have invented a new, original, and ornamental Design for a Toilet Paper Dispenser, of which the following is a specification, reference being made to the accompanying drawings, forming a part thereof.

In the drawings:

Fig. 1 is a front elevational view of the toilet paper dispenser embodying my new design;

Fig. 3 is a top plan view of the toilet paper dispenser shown in Figs. 1 and 2 of the drawings.

I claim:

The ornamental design for a toilet paper dispenser, substantially as shown.

CLARENCE BOORD.
